(57) **CLAIM**

The ornamental design for a wireless sensor as shown and described.

DESCRIPTION

FIG. 1 is a front perspective view of a wireless sensor.

FIG. 2 is a front view of the wireless sensor; and,

FIG. 3 is a rear view of the wireless sensor.

The aspects shown in broken lines are not considered a portion of the claimed ornamental design.

1 Claim, 3 Drawing Sheets*FIG. 1*

FIG. 2

FIG. 3
